US0D1097133S

(12) **United States Design Patent** (10) Patent No.: **US D1,097,133 S**
(45) Date of Patent: ** Oct. 7, 2025

(54) **WEARABLE INJECTOR**

(71) Applicant: **NUOVA OMPI S.r.l Unipersonale**,
Piombino Dese (IT)

(72) Inventors: **Tommaso Borghi**, Milan (IT); **Mattia Cattaneo**, Limbiate (IT); **Pasquale Cirulli**, Vermezzo County Zelo (IT); **Paolo Degan**, Ranica (IT); **Andrea Giacomozi**, Milan (IT); **Gustavo De Souza Messias**, Milan (IT); **Christian Riva**, Cinisello Balsamo (IT)

(73) Assignee: **NUOVA OMPI S.r.l Unipersonale**,
Piombino Dese (IT)

(**) Term: **15 Years**

(21) Appl. No.: **29/962,911**

(22) Filed: **Sep. 13, 2024**

(57) **CLAIM**

The ornamental design for a wearable injector, as shown and described.

DESCRIPTION

FIG. 1 is a perspective view of a medical instrument showing the new design;

FIG. 2 is a top view thereof;

FIG. 3 is a bottom view thereof;

FIG. 4 is a front view thereof;

FIG. 5 is a back view thereof;

FIG. 6 is a left view thereof; and,

FIG. 7 is a right view thereof.

The broken lines shown in the drawing views are included for the purpose of showing portions of the product that form no part of the claimed design.
